UNITED STATES PATENT OFFICE.

WILLIAM HENRY STOREY, OF SOUTHBEND-ON-SEA, ENGLAND.

MEANS FOR AUTOMATICALLY FEEDING AND REVERSING THE DIRECTION OF THE FEED OF PRINTING RIBBONS USED ON TYPE-DUPLICATING MACHINES.

Application filed May 6, 1925, Serial No. 28,319, and in Great Britain May 15, 1924.

The present invention relates to means for automatically feeding and reversing the direction of the feed of the printing ribbons used on type duplicating machines, and has for its object to ensure a positive feeding action, and a positive reverse, said reverse to be effected without depending upon the tautness of the ribbon as hitherto has been the case; and further to make it impossible for the device automatically to reverse at any point other than that almost at the end of the ribbon, that is to say only when there is approximately half a turn of ribbon on the spool from which the ribbon is being unwound.

A further object of the invention is so to construct the mechanism governing these movements that no one spring acts to counteract the action of other springs which hitherto has been the case, the employment of such counteracting springs tending to make the mechanism so delicate that it is sometimes rendered inoperative by dust or even by the viscosity of the lubricant used.

A further object of the invention is to provide a means whereby, on the removal of the spools from the machine the check pawls and feeding pawls become inoperative so that unnecessary wear and noise is eliminated when the machine is being used as a printing machine without a ribbon.

In existing ribbon movements depending upon the reversal of the ribbon by tautness faint impressions are caused to be produced at the points of reversal owing to the fact that before the necessary degree of tautness is obtained the slack of the ribbon on the full spool has to be gradually reduced by the rotation of the winding spool, the ribbon covering the type faces meanwhile being stationary or practically stationary. This continual use of the same portion of the ribbon before reversal (it being stationary) and its re-use immediately after reversal, uses up the ink in the ribbon and consequently faint and useless copies are produced.

Furthermore, owing to the extreme delicacy of the mechanism, the delicacy being such that the friction of the ribbon against the surfaces of say new type, or a substantially full form of type, has been sufficient owing to the dragging action of the type against the ribbon, to produce sufficient taut-

ness to cause the mechanism to reverse the direction of the travel of the ribbon, with the result that the ribbon is used in one portion only, and as the ink becomes used up faint and useless impressions are caused.

The mechanism which ensures positive feeding action and a positive reverse, the said reverse being independent of the tautness of the ribbon, consists of sensing members which are normally held in contact with the ribbon on the spools. On a spool becoming almost empty, that is to say when approximately only half a turn of ribbon is left on the spool from which the ribbon is being unwound, a slot on the spool becomes uncovered thus allowing the sensing member to move towards the centre of that spool under the action of its spring and thus bring an arm attached to the other end of the sensing member into such a position that it prevents the movement of a check pawl which causes the mechanism to reverse.

The removal of the spools from the machine renders inoperative the action of the check pawls and feeding pawls by reason of the fact that the spools have secured to them, or have made in one with them the ratchet wheels which are engaged by the check pawls and feeding pawls.

The invention will now be described more particularly with reference to the accompanying drawings whereon:—

Fig. 1 is a plan view of a cylinder of a rotary type duplicating machine to which the invention has been applied.

Fig. 2 is a sectional side view with the ribbon spools removed.

Fig. 3 is a fragmentary front view showing one of the sensing members for the ribbon spool.

Fig. 4 is a detail view showing the relative positions of the feed pawl, check pawl, and sensing members after reversal of the movement of the ribbon.

Fig. 5 is a detail side view of the mechanism controlling the reversal of the feed pawl by the check pawl.

Fig. 6 is a view of one of the spools with the ratchet wheel secured thereto.

Fig. 7 is a sectional view through the spools showing the ribbon secured therein.

On the drawing the main cylinder is composed of the two ends A B to the peripheries of which is secured the form for the type.

The cylinder is mounted on the shaft 1 which passes through the side frames of the type duplicating machine.

To the shaft 1 is fitted an eccentric 10 to 5 which is attached a yoke 11 the free end of which is fixed in a pivotal manner by the gudgeon pin 12 to a slide 13 which by means of the guide 14 is free to slide in a reciprocative manner in the end A of the cylinder. Or, in the case of machines where the shaft 1 revolves with the cylinder the shaft is capable of freely revolving in the eccentric 10 which is prevented from revolving with the said shaft by means of some 10 suitable connection with the side frame of the machine, such as a pin engaged in both the side frame and the eccentric, from which it will be understood that although the cylinder revolves with the shaft, the eccentric 15 remains stationary and a reciprocating motion is therefore imparted to the slide 13. To the said slide 13 is attached in a pivotal manner a check pawl 20 and a feed pawl 30 by means of the pivot 15 which also 20 passes through the guide 14. The check pawl 20 is fashioned with a bent up arm 21 centrally disposed between its extremities and the said arm is slotted as at 22 in which slides an L shaped shaft 23 on which a roller 25 24 is free to revolve. To the free end of the shaft 23 and exerting a pull upon it (see Fig. 5) is attached a spring 25 the other end of which is fixed to the double sided feed pawl 30 which as previously mentioned 30 is mounted on the pivot 15. The feed pawl is fashioned with teeth 31 and 32, one on each side, and the free end of the feed pawl is moreover fashioned with two curved sides 33 and 34, the two inside faces of which form a pointed tooth 35. Adjacent to one or the other side of this tooth 35 but prevented from contacting during normal working by the bottom of the slot 22 in the double sided check pawl 20 depressing the shaft on which 35 it revolves is the roller 24 previously mentioned, the reason for which will be understood when the action of reversing the mechanism is detailed.

Pivoted in recess A¹ in the end of the cylinder are two spools 40 and 41 to one end of each of which is fixed or made integral therewith the ratchet wheels 42 and 43. The spools are pivoted within the recess A¹ in such a position that the check pawl 20 and feed pawl 30 can make engagement with one or other ratchet wheel. The other end of each spool is removable, the ends being slotted as at 44 to form a spring to retain them. The ribbon C is wound on a sheath 40¹ and the spools are slotted as at 40^a throughout their length and the sheaths 40¹ fit over the spools being split from end to end and having inturned faces 40^b which fit in the slots of the spools while the ends of the ribbon are secured on rods 40^c which are

larger in diameter than the slots in the spools or sleeves, as see Fig. 7.

The sheaths 40¹ as well as the spools 40, 41 are slotted as at 45 and 46 near the ends on which the ratchets are mounted or formed thereon.

In order to prevent the sheath being placed wrongly end for end on the spool and also in order to prevent the sheath from being fitted over the wrong spool projections such as 47 are fixed to the sheath or formed integral therewith by cutting the sheath and bending downwardly portions which engage in the slot 44 only when the correct sheath is being placed on the correct spool in the correct manner, that is to say, end for end. This provision also prevents the ribbon from being placed on the machine in such a manner that the ratchet or feeding mechanism unwinds it. Further to prevent a spool from being mounted on its wrong pivot in the cylinder, one of the pivots 48, 48¹ or 49, 49¹ with the corresponding hole in the end of a spool is made smaller than the other.

Fixed to the cylinder end B in the recess B¹ between the spools is a flat, or leaf spring 50 one purpose of which is to force the spools into driving position with the driving mechanism and to retain them in that position. A further purpose of this spring is to apply sufficient pressure to prevent the ribbon from sagging or coming off from a spool too easily when it is being drawn from the other end thereby maintaining an even contact between the ribbon and the type faces, and to this end the spring 50 is preferably extended so that it makes contact with the spool ends at points as far as possible from the centres of the spools, thereby obtaining leverage.

Pivoted in the recess A¹ of the cylinder end A are a pair of sensing members 60, 60¹. These members are pivoted as at 61 to a housing or bracket 62 secured to a boss formed on the cylinder end A.

The sensing members under the action of the springs 63, 63¹ are being continually pressed towards the centres of the spools but are prevented from entering the slots 45 or 46 because the said slots are normally covered over by the inking ribbon. Fixed to or formed integral with the sensing members 60, 60¹ are trip fingers 64 which are normally held out of engagement with the check pawl 20 because the sensing member is prevented from entering a slot in one of the spools owing to the ribbon which covers it.

The feeding of the ribbon on to one spool and its withdrawl around the faces of the type from the other spool is effected as follows:

When the printing cylinder is set in motion a reciprocating motion is given to the slide 13 through the action of the yoke 11

on the eccentric 10. The feed pawl 30 and the check pawl 20 being hinged on the pivot 15 the action of the spring 25 is to pull their free ends to one or other side of the centre of the pivot. The spool on the side to which they are pulled is the driven or winding spool. The spring attempts to pull the free ends of the feed pawl and check pawl together but is prevented from doing so by stops, if no spool is in position on its pivots.

These stops are formed by the curved sides or faces 33 and 34 of the feed pawl 30 coming into contact with the roller 24. Normally, however, the free ends of the feed pawl 30 and check pawl 20 are stopped by their engagement with one or other of the ratchet wheels 42 and 43 on the spools 40 and 41.

It will thus be seen, therefore, that a movement of the slide 13 with its guide 14 carrying the pivot 15 towards the centre of the cylinder causes the feed pawl 30 to impart a rotary motion to the ratchet wheel (see Fig. 4.) The check pawl 20 which is meanwhile being sprung approximately towards the centre of the ratchet wheel 42 therefore allows any tooth or teeth which is or are forced against it by the feed pawl 30 to pass the check pawl.

It will further be observed that any movement of the guide 14 and slide 13 away from the centre of the printing cylinder therefore forces the feed pawl 30 up to its next feeding position, the check pawl 20 meanwhile preventing the friction between the feed pawl and the ratchet wheel 42 imparting any reverse motion thereto and also helping in the feeding by forcing the ratchet wheel round.

The operation of the mechanism to reverse the direction of travel of the ink ribbon will now be described.

Assuming that the feed pawl 30 and the check pawl 20 are engaging with the ratchet wheel 42 of the spool 40 and are therefore out of engagement with the ratchet wheel 43 of spool 41, that is to say the position is as shown in Fig. 4.

In this figure the sensing member 60 is passed into slot 45 in the spool 40 represented by the ratchet 42. As the ribbon C is wound upon the spool 40, the ribbon forces the member 60 outwardly with the lower part thereof moving to the right in Figure 4, thus permitting the spring which controls the member 60' to draw the bar 65 toward the right in said figure. At each revolution of the ratchet wheel 42 of the spool 40 the ribbon forces the member 60 further away and the trip finger 64 of the member 60', which has previously been gradually forced outwardly by the increased diameter of the ribbon winding on the spool 41 of the ratchet 43, gradually approaches towards the path

of the tooth 26 of the double-ended check pawl 20. Directly all the ribbon leaves the spool 41 of the ratchet 43, member 60', under the action of the spring 63', passes into the slot 46 in the spool and in so doing causes the trip finger 64 to move under the tooth 26 of the pawl 20 in the same manner as illustrated in connection with the tooth 26' shown in Figure 3. The next revolution of the printing cylinder acts upon the slide 13 carrying the pivot 15 upon which the double ended check pawl 20 is pivoted and therefore draws the pivot 15 of the check pawl towards the centre of the cylinder. The free end of the double ended check pawl 20 is prevented from moving by the trip finger 64 of the sensing member 60' on which it is now virtually pivoted. This movement imparts to the double ended check pawl 20 an angular motion much greater than is imparted to it during the normal feeding of the ribbon C, with the result that the roller 24 on the end of the L-shaped shaft 23 is forced into contact with the straight side 33 of the tooth 35 of the feed pawl 30, so forcing the roller 24 away from the pivot 15 by extending the spring 25 on the L-shaped shaft 23 until such time as the roller 24 rests with its centre just over the centre of the tooth 35 against the side 34 of the feed pawl 30 so that the feed pawl and check pawl have their opposite feeding and checking teeth 32 and 26 pulled into engagement with the ratchet wheel 43 of spool 41, that is to say the position of the part is as shown in Fig. 2 and the spool 41 commences to draw the ribbon C from the spool 40.

From the fore-going it will be seen that reversal of the direction of feed to the ribbon is performed without depending upon the tautness of the ribbon to effect reversal which hitherto has been the case with the result that the life of the ribbon is considerably increased and faint impressions do not result when nearing the end of the ribbon.

Moreover, the reversal of the ribbon feed only takes place when one or the other sensing member has been afforded a definite amount of movement towards the center of a spool under the action of a spring and consequently the maximum length of ribbon is used before any reversal takes place. With the known ribbon reversal mechanism the mere drag of the type surfaces against the ribbon during printing has occasioned reversal prior to the maximum amount of travel from one spool to another and consequently uneven wear is afforded to the ribbon.

Again, in known types of ribbon operating devices the feed pawl and check pawl act on the ratchet wheels continuously whether ribbon is on the spools or otherwise. Rotary type duplicating machines are adapted to print either by means of a ribbon or by

inking rollers. In existing machines removal of the ribbon spools for printing from the ink rollers has not prevented wear and tear or noise because the feed pawl and check pawl still act upon one or the other of the ratchets. According to the present invention the ratchet wheels form an integral part of the spools and consequently when the spools are removed from the pivots in the cylinder ends wear and tear and noise is eliminated while using the machine with inking rollers.

Having thus described my invention what I desire to secure by Letters Patent of the United States is as follows:

1. A feeding and reversing mechanism for the printing ribbon of a rotary type duplicating machine, including spools having slots therein, means including a check pawl for positively feeding said ribbon from one spool to another, said pawl having a projection, sensing members each having a trip finger movable into the slot of an associated spool when the ribbon is almost entirely un-

wound therefrom to cause the projection on said pawl to abut said trip finger and thereby prevent movement of said pawl, and means for thereafter effecting a reversal of the feeding of said ribbon.

2. A feeding and reversing mechanism for the printing ribbon of a rotary type duplicating machine, including spools on which said ribbon is wound, means to positively feed said ribbon from one spool to another, said means including a feed pawl and a check pawl, the latter having a slot therein, a common pivot for said pawls, said feed pawl having two curved sides forming a pointed tooth, an L-shaped shaft supported from the feed pawl, a spring connecting said shaft and feed pawl, and a roller housed in the slot formed in said check pawl and supported by said shaft, said roller acting upon either of said curved sides depending upon the direction of feed of said ribbon.

In testimony whereof, I have affixed my signature.

WILLIAM HENRY STOREY.
